UNITED STATES PATENT OFFICE

2,392,696

LAMPSTAND FOR CLOCKS

Benjamin Parks Rucker, Chicago, Ill.

Application August 25, 1944, Serial No. 551,087

1 Claim. (Cl. 240—6.43)

This invention relates to a lamp base for clocks and its principal object is the provision of a base for supporting a clock or other time piece adjacent a concealed or shielded electric lamp which, when the circuit thereof is closed, casts its rays of light only upon the clock face whereby one can observe the time in the dark whenever it is desired to ascertain the time.

It is of no uncommon occurrence for one to wish to know the time during the night, and in a dark room this can only be done by turning on a light to illuminate the clock face. This sudden change from darkness almost always awakens or disturbs any other person occupying the same room.

In accordance with my invention, the base contains a source of electrical energy, such as one or more electric dry cells in series with an electric lamp contained in the base but arranged to cast its light rays through an opening in the top of the base and only upon the clock face. The electric circuit for the dry cells and lamp runs through a conductor cord to a push button or other electric switch located adjacent the user in convenient position to be grasped and manipulated.

Another object is to provide a novel support for the dry cells which support also makes electrical connection therewith and electrically connects them in series with an electric lamp and push button.

Another object is to provide a lamp base for clocks which is simple, inexpensive, easy to construct and assemble and is not likely to become out of order.

With these and other objects and advantages in view, this invention consists in the several novel features hereinafter fully set forth and claimed.

The invention is illustrated in the drawing accompanying this specification, in which:

Fig. 1 is a front elevation of a lamp base for clocks embodying a simple form of the invention and showing a clock supported thereby;

Fig. 2 is a vertical cross section taken on the line 2—2 of Fig. 1;

Fig. 3 is a view looking at the lower side of the base with a certain cover or closure removed; and

Fig. 4 is a diagrammatic view illustrating the lamp circuit.

Referring to said drawing, the reference character 5 designates a rectangular flat hollow base having a top wall 6 and side and end walls 7, 8 projecting down therefrom. Extending up from the top wall along its rear and ends and along the midportion of the top wall is a rib 9 which takes the form of a rectangle that defines a depression in which a conventional alarm clock

designated by the reference character 10 may be placed. The rectangular rib serves to prevent the clock from sliding off the base.

Projecting up from the upper face of the top wall in front of the rectangular rib midway between the ends of the base is a boss or protuberance 11, and projecting down from the lower face of the top wall below the boss 11 is a downwardly projecting boss 12. Extending through the bosses 11, 12 is an opening 13, the axis of which is inclined toward the center of the clock face. Desirably this opening has one part 14 of larger diameter than the part 15 thereby leaving a shoulder 16, the purpose of which will be presently explained. The part 15 of the opening flares outwardly and its outer margin is formed of such size as to confine the light rays from the herein described electric lamp substantially to the clock face whereby no other part of the surroundings will be illuminated.

Seated upon the shoulder 16 of the opening 13 is an electric lamp socket 18 and secured in the socket is an electric lamp 19, the screw shell of which screws into the screw shell of the socket. The socket is held upon the shoulder 16 by an arm 21, preferably soldered or welded to the socket and functioning also as an electrical conductor for the electric circuit. The lamp and socket are further held at the proper angle of inclination to bring the major axis of the lamp in line with the center of the clock face.

A second arm 22 is employed for this purpose. This arm 22 is removably secured to the underside of the top wall 6 by a binding post 23 and nut 24, the binding post extending through a hole in the top wall and the arm having a concave part 25 that bears against the center contact of the lamp. The arm 22 inclines downward from the underside of the top wall at a suitable angle to enable the concave part of the arm to be yieldably pressed against the center contact piece of the lamp.

Secured on the underside of the top wall 6, as by a screw 26 and nut 27, is a metal plate 28, the opposite ends of which are formed with downwardly projecting resilient wings 29, 30, adapted to hold between them several electric dry cells 31, 32, two being shown. The plate 28 may also be formed with downwardly extending tongues 33 which may extend partially around the dry cells to further insure them against accidental displacement.

Between the wing 30 and adjacent poles of the dry cells are interposed contact pieces 34, 35 which are partly enclosed in a flat piece of in-

sulating material 36. The contact pieces 34, 35 are exposed to the adjacent poles of the dry cells and make contact therewith. The tension of the wings 29, 30 holds the dry cells and contact pieces 34, 35 firmly in place.

The contact piece 35 is extended in the form of the arm 21 to the lamp socket and is soldered or welded thereto, and the contact piece 34 is extended in the form of an arm 38 which is secured to the underside of the top wall 6 by a 10 binding post 39 and nut 40.

The two lines 41, 42 of an extension cord 43 extend through a hole in the wall 7 of the base, one line being fastened to the binding post 39 by the nut 40 and the other line being fastened to 15 the binding post 23 by the nut 24. On the other end of the extension cord is a push button 45 of any desired construction. The extension cord is of suitable length to run from the base to a place 20 convenient to the user, for instance to the head of the bed.

A cardboard 46 or other sheet of suitable material serves to enclose and protect the parts contained in the base. The sheet 46 may be held in place on corner pieces 47 of the base by a nut 25 48 threaded upon the screw 26.

The electric circuit for the device may be readily traced from the push button 45 through one line 41 of the extension cord to the contact piece 34, thence through the dry cell 31, wing 29, the 30 dry cell 32, contact piece 35, lamp socket 18, lamp 19 and contact piece 22 and the other line 42 of the extension cord to the push button.

A person wishing to ascertain the time presses the push button, thereby closing the circuit to the lamp which projects its light rays through the opening 13 and upon the clock face, thereby illuminating the same without illuminating the rest of the room.

The base may be formed of Bakelite or other thermoplastic material. It is simple in design and easy to mold. The metal parts are simple stampings and the other parts are standard, obtainable in the open market. The parts are easily assembled and the entire device may be manufactured at a low cost.

From the above it is apparent that I have pro-

vided a simple, inexpensive and practical device whereby the face of a clock or other time piece may be illuminated at will without illuminating any of the surroundings and without exposing 5 the user or other occupant of the room to any glare from the lamp.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

In a lamp base for clocks, a hollow base having a top wall for supporting a clock, said top wall being formed with bosses, one above and one below the top wall and there being an opening through said bossed part of the top wall, the axis of which inclines toward the face of the clock, said opening having one part of greater diameter than the other part which defines an annular shoulder, an electric lamp socket in said opening and bearing against said shoulder, an electric lamp in said socket, a contact piece secured to the underside of the top wall and bearing against the center contact of the lamp whereby to hold the socket against said shoulder, a pair of aligned contact pieces, one of which has an arm rigidly secured to said socket, a sheath of non-conducting material partly enclosing said pair of contact pieces, a metal plate secured to the underside of the top wall and being formed with parallel downwardly projecting resilient wings, dry cells with certain of their poles contacting with said pair of contact pieces and other poles contacting with one of said wings, the other wing bearing 35 against said sheath to hold said pair of contact pieces in contact with the adjacent poles of the dry cells, an extension cord, one line of which leads to the first mentioned contact piece, and the other line of which leads to the other of the 40 pair of contact pieces, and a push button on the other end of the exterior cord.

BENJAMIN PARKS RUCKER.
